Samuel S. Matthes

Attorney

Inventor

UNITED STATES PATENT OFFICE.

SAMUEL S. MATTHES, OF MANSFIELD, OHIO, ASSIGNOR TO THE OHIO BRASS COMPANY, OF MANSFIELD, OHIO, A CORPORATION OF NEW JERSEY.

TROLLEY FROG.

Application filed October 12, 1927. Serial No. 225,715.

My invention relates to a supporting device for trolley wires and particularly that class of supports known as trolley frogs or overhead switch, by means of which the trolley wire is not only supported, but the main and branch trolley wires are brought to and anchored to the trolley frog, which acts as a switch in diverting the movement of the current.

10 The object of my invention is to provide a device in which the trolley wires are detachably secured to a supporting element, and interlocked with the supporting element is a removable trolley pan to which the trolley wires are detachably secured. This construction permits the trolley pan or switching portion of the frog to be removed and replaced at any time without disturbing the connection between the trolley wires and the supporting 15 element. This makes the change from a worn out pan to a new pan a very easy and quick 20 operation.

My invention resides in the new and novel construction, combination and relation of the 25 various parts herein described and shown in the accompanying drawing.

In the drawing:

Fig. 1 is a top plan view of my invention.

Fig. 2 is a side view in partial section.

30 Fig. 3 is a sectional view on the line 3—3 of Fig. 1.

In the preferred embodiment of my invention I employ a body member 1, which comprises a pan 2 provided with projecting arms 3 and 3' to receive the main trolley wire 4, and the obliquely disposed arm 5 to receive the branch wire 6.

The arms are each provided with a groove in which is seated the trolley wires 4 and 6, as shown in the left-hand end of the arm 5 in Fig. 2. The ends of the arms are provided with spaced hook shaped lugs 7. Cooperating with the spaced hook shaped lugs 7 is a member 8, which may be formed a cam tip, for the reason that at one end it is provided with a cam shaped element 9, which engages with the trolley wire to force it into the bottom of the grooves when the cam tip is rotated, as later described. Every cam tip is provided with a groove formed by bendable lips 10 adapted to be clinched around the trolley wire when the cam tip is in final position. The cam portion 9 is provided with projecting headed studs 11, which cooperate with the hook shaped lugs 7 and pivot there-

in. The relation of the face of the cam member 9 to the center of the projecting studs 11 is such that the face of the cam 9 acts as a rotatable wedge to force the trolley wire down into the groove.

The frog is also provided with a removable supporting member 12 provided with a cross-bar 13 in which are openings 14. Projecting from the cross-bar 13 are eye members 15, which may project from the member 13 in a direct horizontal line or out of alinement with the member 13, as shown in Fig. 3. In the latter case the arms are brought down to a point where they coincide approximately with a horizontal plane, in which the trolley wires 4 and 6 rest.

The support 12 is also provided with means for securing thereto the trolley wires 4 and 6, which comprises a compression member 16 and the headed bolt 17.

Connected to the eyes 15 are span wires (not shown) by means of which the supporting member 12 is held in suspension independent of the trolley wires or any other support. This permits the trolley wires 4 and 6 to be secured in position with relation to the support 12 and held in suspended position by the span wires, which may be connected to the eye members 15. In some cases the span wires are entirely done away with and the member 12 held in suspension by the trolley wires alone.

Projecting from the pan member 2 are internally threaded studs 18 which register with the openings 14 in the suspension member. When the suspension member and body member 1 are in relative positions, the two are interlocked against relative lateral or longitudinal movement, but not against transverse or vertical movement. It is sometimes found desirable to prevent transverse movement, as well as longitudinal and lateral movement, and this is secured by means of the headed studs 19 which detachably secure the body member and supporting member together against transverse movement and the lugs 18 prevent relative lateral and longitudinal movement.

To install my improved frog upon the trolley wires 4 and 6, the support member 12 is first removed from the body member 2. The trolley wires are then positioned between the members 13 and 16 and the stud 17 drawn up tight to grip the trolley wires in position with respect to the support 12. The cam tips

8 are then removed from the arms by merely unhooking them from the hook shaped lugs 7. The pan is then brought into position with respect to the support 12, and, if desired, may be held in this position by means of the studs 19. One of the trolley wires is bent down by means of the hand or wrench or other tool, so that it is seated in the groove of its arm sufficiently to allow the cam tips 8 to be re-positioned with respect to the hook shaped lugs 7 when the cam is in an upright position or angularly disposed to said upright position, as by its being tipped sufficiently backward from a vertical position to permit its being interlocked with the lugs 7.

The cam tip 8 having been re-positioned, the same is rotated about the axis of the studs 11 until it assumes the position shown in Fig. 2 with respect to the trolley wire.

Having positioned one of the cam tips, the same process is carried out with the other two cam tips. After the cam tips have been properly positioned, then the lips 10 are bent or peened about the trolley wire 6, which locks the cam tip to the trolley wire against rotative movement about the axis of the projecting studs 11 positioned in the hook shaped members 7.

In order to remove the body member 2, it is necessary to spread the lips 10, which is easily done with a thin edged cold chisel, and then to rotate the cam tips 8 backwardly until they can be withdrawn from the hook shaped lugs 7. If the headed studs 19 are used, they will support the body member 2 after the cam tips 8 have been removed, and if the studs 19 are employed then they are removed and the body member 2 can be removed and the trolley wires will remain secured to the support member 12 without being disturbed.

To apply a new pan, the process described above is repeated, but it is not necessary, of course, to apply a new support member 12 or disturb its relation to the trolley wire.

The use of the studs 19 is not necessary, as the tension in the trolley wires tends to hold the body member 2 up against the support member 12 when the cam tips 8 are in operative position, but if the studs 19 are not used, then the cam tips alone support the body member 1 and when the cam tips have been removed there is a possibility of the body member being dropped and may injure someone on the ground, therefore, the studs 19 act as a safety member and a convenience in applying or removing the body member 2.

There are, of course, variations which will suggest themselves to one skilled in the art, but I do not wish to be limited other than by my claims.

I claim:

1. A trolley frog comprising a body member having a plurality of channeled members each to receive a trolley wire, a support mem-

bers secured to the body member against relative longitudinal and lateral movement, means on the support member to receive the trolley wires and hold them against movement relative to the support member and a rotatable wedge pivotally secured to each channeled member to engage and clamp the trolley wires in fixed relation to the channeled members but permitting the removal of the body and channeled members at will without disturbing the connection of the wires at the support member.

2. A trolley frog comprising a body member having a plurality of channeled members each to receive a trolley wire, a support member secured to the body member against relative longitudinal and lateral movement, means on the support member to receive the trolley wires and hold them against movement relative to the support member, a cam tip pivotally secured to each channeled member and comprising a rotatable wedge to clamp the trolley wires in fixed relation to the channeled members and a channeled member having bendable lips projecting from the rotatable wedge to receive the trolley wire and lock the cam tip against pivotal movement.

3. A trolley frog comprising a body member to be attached to a trolley wire and having a channel therein to receive the wire, a support member removably secured to the body member against lateral and longitudinal movement relative to the body member, means on the supporting member to secure the trolley wire thereto, above and spaced from the body member, a cam tip pivotally secured to the body member having a portion to engage the trolley wire and draw it into and hold it in engagement with the bottom of the channel, the support member and the cam tip operating together to hold the body member and the trolley wire in fixed relation but detachable at will and the cam tip having a channeled portion to receive and engage the trolley wire to lock it against rotation relative to the wire.

4. A trolley frog comprising a body member, a support member, a channel in the body member to receive a trolley wire, holding means to detachably hold the trolley wire in the groove, means on the body member to interlock with means on the support member to prevent relative lateral and longitudinal movement, gripping means on the under-face of the support member to receive and hold the trolley wire in fixed relation, the body member being removable when the holding means releases the trolley wire.

5. A trolley frog comprising a support member, means to secure trolley wires thereto, means on the support to attach supporting span wires thereto, a replaceable switching pan below said trolley wires and secured to the support member against lateral and lon-

itudinal movement and means to detachably secure the trolley wires to the pan at points remote from the support.

6. A trolley frog comprising a body member, means to detachably secure a trolley wire thereto, a supporting member, means to secure the trolley wire to the support and other means to detachably secure the support to the body member without disturbing the relation of the trolley wire to the support and prevent relative transverse, lateral and longitudinal movement of the support and body members.

7. A trolley frog comprising a body member, means to detachably secure a trolley wire thereto, a supporting member, means to secure the trolley wire to the support and other means to detachably secure the support to the body member without disturbing the relation of the trolley wire to the support and prevent relative lateral and longitudinal movement of the support and body members.

8. A trolley frog comprising a body member, means to detachably secure a trolley wire thereto, a supporting member, means to secure the trolley wire to the supporting member, projecting means on one member entering recesses on the other member to prevent relative lateral and longitudinal movement of the members and means to detachably interlock the members against transverse movement.

9. A trolley frog comprising a body member, means to detachably secure a trolley wire to opposite ends of the body member, a support member, means to secure the support to the body member intermediate its ends against relative lateral and longitudinal

movement, means to detachably secure the trolley wire to the support member against relative movement and raise the trolley wire 40 at said point of securing above the normal level of the trolley wire adjacent the ends of the body member to prevent displacement of the support and body members in a transverse direction. 45

10. A trolley frog comprising a body member and a support member, the support member provided with means to detachably secure a trolley wire thereto to support the wire, means on the body member to detachably secure the trolley wire thereto to support the body member and means to detachably secure the support to the body member to support the body member thereby when the means supporting the body to the trolley 50 wire is released. 55

11. A support for a trolley wire and switch pan comprising a body having openings therein to receive projections on the pan, means to detachably receive and grip the trolley wire and means projecting from the body member to secure supporting span wires thereto. 60

12. A support for a trolley wire and switch pan comprising a body having openings 65 therein to receive projections on the pan, means to detachably receive and grip the trolley wire and means projecting from the body member to secure supporting span wires thereto at a point below the trolley wire 70 where secured to the support.

In testimony whereof I affix my signature.

SAMUEL S. MATTHES.
